UNITED STATES PATENT OFFICE.

THOMAS R. McCLOSKEY, OF SALT LAKE CITY, UTAH.

CURTAIN-STRETCHER.

1,063,990.

Specification of Letters Patent. Patented June 10, 1913.

Application filed April 12, 1912. Serial No. 600,452.

To all whom it may concern:

Be it known that I, THOMAS R. McCLOSKEY, a citizen of the United States, residing at Salt Lake City, in the county of Salt Lake and State of Utah, have invented a new and useful Improvement in Curtain-Stretchers.

The object of my invention is to provide a curtain stretcher on which the curtain may 10 be quickly and readily fastened, readily removed, and to provide a curtain stretcher that is simple in construction, neat in appearance and cheap to manufacture.

With these and other objects in view, my 15 invention consists in the novel features of construction and combination of parts, as will be hereinafter more fully described and pointed out in the claims.

In the drawings: Figure 1 is a front view 20 of my invention. Fig. 2 is a side view of my invention. Fig. 3 is a sectional view through *a—a* Fig. 1. Fig. 4 is a view showing my invention closed. Fig. 5 is an enlarged plan view of the corner clamps forming part of 25 my invention. Fig. 6 is a side view of the above clamp. Fig. 7 is a front view of the corner clamp. Fig. 8 is an end view of the curtain hooks and rod. Fig. 9 is an enlarged detail view of the hook and rod showing the 30 means of securing the rod to the slats. Fig. 10 is a side elevation of one style of hook and rod used.

Similar numerals refer to similar parts throughout the several views.

35 1, 1' denotes the slats forming the four sides of the curtain stretchers. 2 denotes the central frame member, 3 are the curtain hooks, which are firmly secured into the rod 4. The hooks 3 are turned back when 40 not in use, as shown by the dotted lines Fig. 9. The rod 4 is secured to the slats 1, by means of staples 5 which are driven into the slats 1, thus allowing the rod 4 to be turned at will of the operator by taking hold of any 45 hook. The rod 4 rests within the groove 6. The clamps 7 located at the corners of the stretcher, are for the purpose of firmly securing the slats together, by tightening up on the thumb screws 8. The reinforcing 50 clamp 9 is located in the center of the stretcher, having slotted holes 10 through which pass the thumb screws 11, the head 12 of the thumb screws 11 being in a wedge shape, for the purpose of allowing the head to fit snugly up to the angles of the clamp 13. The clamp 13 is for the purpose of securing

the central frame member 2, to the sides 1 of the frame. A slotted hole 14 is cut into the flange 15 of the clamp 13, to allow the thumb screw 11 to pass through. By tightening up on the thumb screw 11 the reinforcing clamp 9 will be drawn tight up to the slats 1, and the clamp 13 will also be drawn firmly up to the central frame member 2.

65 The corner clamps 7 are made in such a shape that the slats may be moved in and out at the will of the operator, the upper portion 16 being bent in the form of a loop having the sides closed while the ends are 70 open to allow the slats to be placed within the loop, while the lower portion 17 is open on three sides.

In assembling my invention, I take the 75 slats 1 and 1' and place them into the corner clamps 7, then tighten the thumb screw 8, thus securing them firmly in their relative positions. Now I place the other end of slats 1 into the reinforcing clamp 9, then place the clamp 15 under the reinforcing 80 clamp 9, then pass the thumb screws 11 through the slots 10 and 14. Now I place the central frame member 2, into the clamp 13 and then tighten upon the thumb screws 11, which firmly secures the center brace 2 85 and the slats 1 together.

When I desire to close up my invention for shipping or putting away, I unscrew the thumb screws 8 and slip off the slats 1', then unscrew the thumb screws 11 and take 90 out the central frame member 2, then fold the slats 1 together and lay them face to face, and then place the slats 1' at their sides, as shown in Fig. 4.

95 It will be observed that by the use of clamps of the peculiar construction shown in Fig. 5, that I obviate the necessity of having slots or grooves in the slats, which weaken the same, and that the construction of these corner clamps is such that the slats 100 readily and smoothly glide through the clamps when operated. It will also be observed that I have provided a center clamp 9 of such construction that the weakest part 105 of the stretcher viz, the center of the two sides is considerably strengthened.

The object of the slots in the center clamp through which the thumb screws pass, is to permit the ends of the two slats of one side to pass radially by each other, when closing 110 the same at right-angles to each other, and yet to permit the said slats when opened to

be forced toward the center, so that the two ends may butt up against each other, and thus be secured in position by tightening the thumb screws. It will be readily understood that this freedom of movement obtained by the said slots makes for the strength of the stretcher.

What I claim as my invention and desire to secure by Letters Patent is:

- 10 1. In a stretcher or drier, in combination with frame members, the middle clamp having two longitudinal slots toward the middle portion of the said clamp, through each of which a thumb screw having an elongated head passes, a clamp for securing the central frame member having on each side thereof a slot identical with the slots in the said first mentioned clamp, and through which the said thumb screw passes, having 15 its elongated head on the same side of the frame as the central frame member; the said slots being of such length as to permit the ends of each half of the longitudinal frame members to abut and yet to slide 20 apart sufficiently to turn inwardly on the said screw, and the length of the said elongated head being such as to prevent the said thumb screw from turning on account of said head bringing up against the middle 25 portion of said last mentioned clamp.
2. In a stretcher or drier of the character described in combination with slats forming the four sides of the frame and a central frame member, the central frame member 30 being secured to the middle portion of the sides of the said frame by a clamp containing a longitudinal slot in each end of the same, and on each side of the loop

through which the middle member of the said frame passes the reinforcing clamp 40 housing the middle ends of the side slats, a thumb screw passing through the said slot in the said first mentioned clamp, and through two identical slots located toward the center of the middle portion of the reinforcing clamp, and on each side of the central member of the said frame, a thumb screw having an elongated head abutting against the said middle frame member and passing through the slots in both of the 45 said clamps.

3. In a stretcher or drier, the combination of side bars 1, 1, having their inner ends abutting, the clamp 9, embracing the two said ends and bridging the abutting joints 50 of the said ends of the said clamp, having longitudinal slots 10, 10, on each side of the central frame member 2, the said middle member 2 passing through the clamp 13, the said clamp 13 being attached to the said frame and secured thereto and to the clamp 9 by thumb screws 11, having elongated heads and passing through the longitudinal slots 14, 14; the said slots 14, and 10 being 55 of such length as to permit the folding inwardly upon themselves of the members 1, 1, when turned upon the thumb screws 11, 11, and the elongated heads of the said thumb screws being of such length as to prevent the turning around of the said head 60 when the thumb screws are screwed upon it.

THOMAS R. McCLOSKEY.
